UNITED STATES PATENT OFFICE

1,990,696

COP WINDING MACHINE

Henry G. Johnson, East Hampton, Conn., assignor to Summit Thread Company, East Hampton, Conn., a corporation of Connecticut

Application April 18, 1933, Serial No. 666,650

12 Claims. (Cl. 164—69)

This invention relates to machines of the type in which a number of cops of thread are simultaneously wound on a tube, and the tube is severed between these simultaneous windings so as to make independent bobbins. It is related to machines of the type disclosed in my United States Patent 1,909,181, granted May 16, 1933; and the present embodiment of the invention is shown in connection with that specific machine. 10 However, the protection which I claim is not so limited, but applies to any machine of the type containing a spindle for holding the tube on which thread is wound, a cutter for severing the tube between individual windings of thread, and 15 a receiver for the finished bobbins or cops.

My present object is to provide in connection with machines of this character, automatic means for shifting the tube severing cutters so that they will present new parts of their edges 20 for each cutting operation, and a multiple receiver or magazine to receive and hold the completed cops or bobbins. The invention consists in the means for accomplishing these objects hereinafter described and all equivalents thereof 25 containing the same principles within the scope of the appended claims.

In the drawings,—

Fig. 1 is a plan view of the winding and delivering end of the machine of my said prior patent application, showing the new features of the present invention applied thereto;

Fig. 2 is a rear elevation of the same;

Fig. 3 is a sectional view of the tube cutters and their adjusting means, shown on a larger scale than the preceding figures, taken on line 3—3 of Figs. 1 and 7;

Fig. 4 is an enlarged side elevation of the cop receiver as viewed from the side opposite to that shown in Fig. 2;

Figs. 5 and 6 are detail sectional views taken on lines 5—5 and 6—6 respectively of Fig. 4;

Fig. 7 is an end elevation of the machine as viewed from the left of Figs. 1 and 2, and drawn to the same scale as Figs. 3 and 4;

Fig. 8 is a cross section on line 8—8 of Fig. 2, drawn to the same scale as Fig. 7.

Like reference characters designate the same parts wherever they occur in all the figures.

The drawings show as much of the framing and operating parts of the machine shown in my prior patent as is needed to explain the new invention. The numeral 10 represents the winding spindle which is surrounded by a tube 11, of paper or other suitable material, on which the thread is wound. Separate threads are led

through guiding eyes 12 to an oscillative thread guide 13, which has spaced apart eyes for the separate threads and moves them back and forth as the spindle is rotated, and through distances in each direction less than those between its adjacent eyes, so as to build up separate and independent windings side by side on the tube. Circular disk knives 14 are operated to sever the tube between the windings, and a pusher 15 displaces the finished cops from the spindle into a receiving magazine 16.

The disk knives are spaced apart by intermediate spacing sleeves 17 and are fastened to a shaft 18; their distance apart conforming to the width and spacing of the cops. The ends of this shaft are mounted rotatably in the arms 19 and 20 of a holder 21 which in turn is secured to a swing frame 22 having a hub 23 which is clamped and secured to an oscillatively mounted shaft 24. Said shaft carries an arm 25, shown in Figs. 7 and 8 by dotted lines because it is obscured from direct view by the machine frame, and this arm is connected with a biasing spring 26 which tends to withdraw the knife carrier from the winding spindle. The latter and the knives are further operated and controlled by a cam 27 through the medium of a slide 28 which carries an adjustable pusher 29 bearing on an abutment 30 carried by the swing frame. A follower roll 31 on the side of this slide is held against the cam surface by the action of spring 26. The cam surface includes a rise 27a which advances the knives to cutting position, as shown in Fig. 8, a high dwell 27b, and a descent 27c which permits retraction of the knives to the position shown in Fig. 7, where they are held by the low dwell which forms the balance of the cam circumference.

In the machine of my prior patent the knives were freely rotatable and were caused to roll in peripheral contact with the thread tube during cutting. But in the present invention they are prevented from rotation while cutting and are given a rotative adjustment about their axis through a prescribed angle each time they are advanced to cutting position.

In the illustration herein the means for preventing rotation of the disk knives during cutting is a friction brake 32 bearing on the side of the endmost disk. This brake is a pin or block slidingly mounted in a guide 33 which forms part of the carrier arm 20. A spring 34 in the guide presses the brake against the disk and reacts against an adjustable abutment 35, made as a screw threaded into the guide and equipped with

a lock nut 36. A ratchet wheel 37 is keyed to the knife spindle 18 beside the other arm 19 of the carrier and is engaged by a pawl 38. Such pawl is pivoted to swing freely on a stud 39 which projects from the adjacent side plate or support 40 of the machine frame. These parts are suitably dimensioned and positioned to locate the pawl in the space between the carrier arm 19 and the nearest disk knife, clear of either, and with the pawl extending in approximate coincidence with the path traversed by the under side of the ratchet wheel as the knives are advanced and retracted. A leaf spring 41 is made fast at one end to the pawl 38 and is free at the other end, bearing on an adjacent part of the swing frame with exertion of force tending to hold the pawl against the ratchet wheel yieldingly. The cooperating teeth of the ratchet wheel and pawl are complementally so inclined as to effect positive engagement as the knife is carried toward the winding spindle, thereby turning the knife, and to slip over one another when the knife is moved away from the spindle. Thus a fresh arc of each knife is advanced to the tube after each back and forth swing of the knife carrier.

The receiving magazine 16 is made with a number of compartments or channels extending longitudinally in different sides, and spaced equiangularly around a common central axis. These channels are open from end to end of the magazine and are of suitable shape and dimensions to contain each a row of axially alined cops. The magazine is mounted to rotate about the above named axis on an axle rod 43 which projects parallel with the spindle axis from a bracket 44 suitably secured to the machine base as, for instance, by being pinned or clamped to a shaft 45 which protrudes from the base. All of the receiving compartments or passages referred to are equidistant from the pivot axis, and the pivot shaft is spaced to one side of the spindle axis a distance equal to that between the axis of the magazine and the axis or longitudinal median line of any compartment. Therefore, by turning the magazine about its axis any one of the receiving compartments may be located in alinement with the winding spindle. It should be noted that the outer end of the spindle and the adjacent end of the carrier are close together; that is, the distance between them is less than the length of the standard cop, whereby cops displaced by the pusher 15 enter the compartment which is at that moment alined with the spindle.

For turning the magazine there is a pawl and ratchet mechanism consisting of abutments or teeth 46 protruding from one end of the carrier and a pawl 47. The abutments are made as pins set into the magazine equidistant from the axis thereof and equiangularly arranged about the axis, in a number equal to the number of compartments.

The pawl is pivoted to a carrier arm 48 which swings about the shaft 45 and is connected with a lug 49. The latter is actuated by a roll or stud 50 on an arm 51 carried by a rock shaft 52 which is journaled in a bracket 53. A second arm 54 fixed to said rock shaft carries a roll or stud 55 bearing on the rim of a cam disk 56. Said cam has a rising portion 56a, a descending portion 56b, and intermediate high and low dwells.

This last cam is associated with the cam 27, and with other cams controlling actions of other parts of the machine, and its features are so

timed as to cause one of the compartments of the magazine to stand stationary in line with the spindle while a series of cops are being displaced from the spindle by the pusher 15, and to bring another compartment into receiving position during the winding phase of the cycle of the machine.

In the opposite end of the magazine from the ratchet abutments are notches 57, equal in number and similar in spacing to said abutments; and a pin 58 is contained in a socket in a sleeve 59 secured to the axle rod 43. A spring 60 presses this pin toward the magazine. The pin and notches have inclined engaging faces and are so located that when any one of the receiving compartments is correctly alined with the winding spindle, the pin projects into one of the notches and holds it there; while it is displaceable by the cam action of such contact faces when the magazine is turned by the pawl.

This magazine provides storage capacity for a large number of cops in a small space. It may be made long enough in axial direction to receive the cops from two or more winding operations in each compartment; in which case it need not be emptied until it has made a corresponding number of revolutions. That is, after having made one revolution and received cops in all its compartments, the next revolution results in more cops being added to those already in the compartments.

It will be understood from the foregoing description, and by reference to the prior patent on which the present disclosure is based, that the operations of the knives and magazine are timed in proper correlation with the other phases of the cycle of the complete machine. It will further be apparent that these new features may be combined with other winding machines than the one disclosed in said patent; machines which may be more or less different from that one.

What I claim and desire to secure by Letters Patent is:

1. The combination with means for supporting and rotating an article to be cut into lengths, of a disk knife and means for bringing different arcs of the knife edge into contact with such article comprising the combination with means for moving the disk knife toward and away from the article, of a ratchet connected with the knife and a pawl mounted on a relatively stationary part of the machine in position to engage said ratchet wheel and rotate the same during the displacement of the knife in one direction.

2. In a cutting mechanism, the combination of a disk knife, a carrier on which said knife is rotatably mounted, means for moving said carrier back and forth, a ratchet wheel connected with the disk knife, and a relatively stationary pawl arranged to impart rotation to the ratchet with movement of the knife carrier in one direction only.

3. In a cutting apparatus, an oscillative knife carrier, a disk knife rotatably mounted on said carrier, a ratchet wheel connected with said disk knife, and a pawl cooperatively associated with said ratchet to impart rotation thereto when the carrier is moved in one direction and to permit passage of the ratchet without rotation when the carrier is moved in the opposite direction.

4. In a cutting apparatus, the combination with means for supporting and rotating the article to be cut, of a disk knife, means for advancing the knife into cutting position and retracting it therefrom, means for restraining the knife from rotation while cutting the tube, and

means for rotating the knife to present different portions of its edge to the tube.

5. In a tube severing machine, the combination with means for supporting and rotating a tube, of a disk knife, means for advancing the knife into cutting position and retracting it therefrom, means for restraining the knife from rotation while cutting the tube, and means organized to operate during times while the knife is out of cutting position to turn the knife so that a different part of its edge is presented for a subsequent cutting action.

6. In a cutting apparatus, the combination with means for supporting and rotating an article to be cut into lengths, of a gang of disk knives arranged side by side for cutting the article, a knife carrier, a shaft rotatably mounted on said carrier on which said knives are secured, a ratchet wheel secured to said shaft, means for moving the carrier back and forth in a path which brings the knives into contact with the article and withdraws them therefrom, and a pawl connected to a stationary part of the machine in position to cooperate with the ratchet wheel for turning the ratchet wheel during the translative movement of the carrier in one direction.

7. The combination with means for supporting and propelling an article to be cut into lengths, of a disk knife, means for supporting said knife in position to cut the article, means for normally preventing rotation of the knife while in cutting action upon the article, a ratchet and pawl mechanism in rotation imparting relationship to the knife, and means for actuating said pawl and ratchet mechanism from time to time to turn the knife sufficiently to bring different arcs of its edge into engagement with the article.

8. In a cutting apparatus, the combination with means for supporting and propelling an article to be cut into lengths, of a disk knife, a knife carrier, a shaft rotatably mounted on said carrier on which said knife is secured, a ratchet wheel secured to said shaft, means for moving the carrier toward and away from the article, a pawl connected to a stationary part of the machine in position to cooperate with the ratchet wheel so as to turn the same during the movement of the carrier in one direction, and a spring connected to the pawl and bearing against a part of the carrier in a manner to hold the pawl yieldingly up to the ratchet wheel.

9. In a cutting apparatus, the combination with means for supporting and propelling an article to be cut into lengths, of a disk knife, a knife carrier, a shaft rotatably mounted on said carrier and on which said knife is secured, a ratchet wheel secured to said shaft, means for moving

the carrier back and forth to carry the knife up to and away from the article, and a pawl connected to a stationary part of the machine and provided with a series of teeth extending in a line of which the direction is substantially the same as that in which said ratchet wheel is carried by the carrier, the length of such pawl being sufficient to maintain a portion of its series of teeth in connection with the ratchet wheel in all positions of the latter.

10. In a cutting apparatus, the combination with means for supporting and propelling an article to be cut into lengths, of a disk knife, a knife carrier, a shaft rotatably mounted on said carrier and on which said knife is secured, a ratchet wheel secured to said shaft, means for moving the carrier back and forth to carry the knife up to and away from the article, a pawl connected to a stationary part of the machine and provided with a series of teeth extending in a line of which the direction is substantially the same as that in which said ratchet wheel is carried by the carrier, the length of such pawl being sufficient to maintain a portion of its series of teeth in connection with the ratchet wheel in all positions of the latter, and a spring acting between the pawl and knife carrier with tendency to hold the pawl against the ratchet wheel permitting it to yield away therefrom.

11. In a cutting apparatus, the combination of means for supporting and rotating an article to be cut into lengths, of a gang of disk knives arranged side by side for cutting the article, a knife carrier, a shaft rotatably mounted on said carrier and on which said knives are secured, means for moving the carrier back and forth so as to bring the knives into and out of contact with the article, means for restraining the knives from rotation while in cutting contact with the article, a ratchet wheel secured to said shaft, and a pawl connected to a stationary part of the machine in position to cooperate with the ratchet wheel for turning it during the translative movement of the carrier in one direction.

12. In a cutting apparatus, the combination of means for supporting and propelling an article to be cut into lengths, of a disk knife, a carrier on which said knife is mounted with capacity for rotation about its center, means for advancing and retracting said carrier so as to bring the knife into and out of cutting position, a spring pressed friction member mounted in the carrier and bearing against the knife to prevent rotation thereof while in cutting contact with the article, and means for turning the knife so as to present different portions of its edge to the article.

HENRY G. JOHNSON.
